CONDENSER FOR REFRIGERATING PLANTS

Application filed January 24, 1928. Serial No. 249,078.

This invention relates to improvements in condensers for refrigerating plants, and in particular to means whereby the operation of such condensers is improved.

It has long been known to employ condensers in which a multiplicity of condensing units or coils were connected between the inlet and outlet headers, these coils all being chilled in some manner, usually by a fluid, so that the compressed refrigerant gas entering the condenser was chilled therein below its critical point and the refrigerant liquefied so that it flowed downward in the respective coil and entered the outlet header. It has further been proposed to arrange the respective condenser pipes in a vertical column and to cause water as a cooling fluid to trickle downward successively over the walls to produce the chilling effect thereof. Since the water was heated successively by the condenser pipes, the temperature of the water at encountering the uppermost pipe was less than its temperature at the lowermost pipe. The condensing capacity of the uppermost pipe was therefore greater than the condensing capacity of the lowermost pipe: and theoretically, more gas should flow into the uppermost pipe, be condensed therein and pass to the outlet header.

In practice, however, it has now been found that the presence of quantities of non-condensable gas, commonly known as "foul gas" which enters with the hot compressed refrigerant gas, causes a blocking of the operation of the condenser. This foul gas, at the same temperature and pressure as the compressed refrigerant gas and mixed therewith, would pass in a substantially regular proportion to this gas into the several condensing pipes. Since the pipes were of uniform size for ease of construction, each took approximately the same quantity of gas, and since the condensing effect of the lowermost pipe was only one-half or one-third as great as that of the uppermost pipe, the uppermost pipe received at all times a greater quantity of foul gas than the lowermost coil.

Further, in actual operation it was found that the variation of condensing effects be-

tween the uppermost and the lowermost pipe was such that mixed refrigerant and foul gas would actually pass through the lowermost pipes without condensation, entering the outlet header. The uppermost pipe, being of greater condensing efficiency, causes a full condensation of substantially all refrigerant gas therein before its outlet end is reached by the flowing gas, so that in effect the back pressure in the outlet header by reason of the mixed gases entering from the lowermost pipes, causes a return of such mixed gases into the uppermost pipes, with condensation of the refrigerant gas therein. As a result of this, a pocket of foul gas is formed intermediate the length of the upper pipes, at approximately the point where the mixed gases entering from the inlet header come into contact with the mixed gases entering from the outlet header. This pocket remains quiescent and gradually extends along the length of the upper pipes, thus seriously decreasing the efficiency of the whole condenser.

These conditions were true for practically all of the pipes in the upper half of the condenser bank, and in aggravated instances extending even to the lower half of the bank.

The present invention relates to means for overcoming this blocking of the upper and highly efficient condensing pipes, by restricting the relative flow of gas through the pipes so that the pressure in each pipe at the outlet is substantially the same, so that in each pipe the foul gas is carried along into the outlet header, and each pipe works at the fullest efficiency of which it is capable.

In addition to the method of accomplishing this result, this invention further relates to an apparatus for carrying out the method: and a still further feature is a particularly simple apparatus for this purpose.

On the accompanying drawings, illustrating such a convenient apparatus for practicing the method by way of illustration of the invention, there is shown:

In Figure 1, a conventional diagram of a condenser for a refrigerating plant;

Fig. 2, a view on larger scale of the inlet header, in vertical section, with the pipe ends

likewise in section to show the regulating means.

On these drawings there is shown an inlet header 10 which is substantially a vertical pipe having a hot compressed gas inlet 11 connected thereto and controlled by an inlet valve 12. The outlet header 13 has a drain pipe 14 with a regulating valve 15 to permit the flow of the liquefied refrigerant into the receiver 16. At the top of the outlet header 13 is a pipe 17 having a control valve 18 for the withdrawal of foul gas.

Connecting the inlet header 10 and the outlet header 13 is a plurality of condensing pipes 19 arranged in multiple, and illustrated as being arranged substantially in a vertical column, i. e., one above another in a bank; it is customary to have these pipes slope on an incline from the inlet to the outlet header, so that the liquefied gas flows freely by gravity into the outlet header, and by reason of the customary great length of these tubes they are often bent back and forth in a zig-zag formation to obtain a maximum chilling effect, so that the refrigerant gas entering each of the multiple pipes may be completely chilled therein to form a liquid.

Above the bank of condensing pipes is disposed a trough 20 receiving water from the pipe 21 and permitting it to trickle downward in succession over the several pipes. The water at a relatively low temperature comes in contact with the top pipe 19^a and produces a chilling of this pipe to below the critical temperature of the hot compressed refrigerant gas. The water is heated thereby slightly, and as it trickles downward onto the next succeeding coil 19^b, the lowest temperature to which it can reduce this next pipe is above the temperature of the upper pipe 19^a. From the second pipe 19^b it trickles to the third, which it cools to a slightly less extent, and so on successively for the several pipes of the bank 19. It will be understood that for the purpose of this invention it is not essential that the pipes of the bank 19 be arranged in vertical planes, but may be in staggered relationship, or any other arrangement wherein one pipe is cooled to a lesser extent than another pipe: the same fluid being employed for the successive pipes for reasons of economy of operation.

For simplicity and cheapness of construction a form of construction of the pipes has been shown in Fig. 2 which is excellently adapted for the practicing of the present invention, and employs a drawn sleeve for the inlet manifold 10 which is closed at its upper end by a domed flange 10^a and at its bottom by a dome 10^b: these parts are preferably welded together at the factory. Each of the pipes of the bank 19 is of the same diameter and is passed through an aperture in the wall of the inlet header 10, and is secured mechanically thereto and the aperture is hermetically

sealed to the atmosphere by a weld joint.

According to the present invention, the inlet to each of the pipes of the bank 19 is obstructed by a closing plate or disk 22^a, 22^b . . . 22^x. Each of these plates has an aperture 23^a, 23^b . . . 23^x through it, and these apertures successively decrease in area downwardly, so that the aperture 23^a is larger than the aperture 23^b and so in succession until the aperture 23^x of the lowermost pipe in this illustration is the smallest, being the pipe which has the highest temperature by reason of the increase of the temperature of the cooling fluid passing over the successive pipes and arriving at the lowermost pipe. These plates may be slipped in position and held there by a small weld, and it is not necessary to weld them in position for the entire periphery of the plate, since small leaks are of relatively no importance.

By design, the relative areas of the apertures 23^a, 23^b . . . 23^x are such that the flow of gas through the respective pipes 19^a, 19^b . . . is proportioned to the condensing capacity of the respective pipe, so that the gas pressure at the end of the respective pipe opening into the outlet header 13 is practically the same for each pipe, and hence there is no return of gas from the outlet header 13 to any pipe; but each pipe operates for its entire length for the condensation of the compressed refrigerant gas therein, and the discharge at the end of the respective pipe is substantially composed of liquefied refrigerant and of foul gas; the latter being drawn off either continuously or from time to time through the foul gas pipe 17.

It will be understood that any person skilled in the art may design the size of the apertures 23^a, 23^b . . . 23^x in conjunction with the cross sectional area and the length of the coils 19^a, 19^b, etc., and in conjunction with the known operating conditions of compression pressure, receiver pressure, water or other cooling fluid temperature, etc., according to well known and recognized laws and commercial practice.

In particular, it will be noted that the quantity of gas admitted to each pipe varies in an inverse proportion to the temperature of the pipe insomuch as the coolest pipe receives more gas than the warmest pipe.

The illustrated form of the invention is not a limitation upon it: since it is obvious that the invention may be practiced in many ways within the scope of the appended claims.

What is claimed as new is:

1. In a condenser for a refrigerating plant, an inlet and an outlet header, a plurality of condensing pipes in multiple connecting said headers, whereby to receive gas from the inlet header and deliver the condensate to the outlet header, devices whereby to impart different chilling effects to said respective pipes, and means located adjacent the inlet header

to apportion to each pipe a quantity of refrigerant gas substantially equivalent to the condensing capacity of the respective pipe.

2. In a condenser for a refrigerating plant, 5 an inlet and an outlet header, a plurality of condensing pipes in multiple connecting said headers, said pipes being arranged at different elevations, devices whereby to impart different chilling effects to said respective pipes 10 whereby a greater chilling of an upper pipe is produced and a relatively lesser chilling of a lower pipe, and means located adjacent the inlet header to limit the flow of refrigerant gas into the lower pipe to the quantity substantially equivalent to the condensing capacity of the respective pipe.

3. In a condenser for a refrigerating plant, an inlet and an outlet header, a plurality of condensing pipes in multiple connecting said 20 headers, means to pass a cooling fluid over the pipes to produce different cooling effects in different pipes, said pipes being each arranged so that the connection to the outlet header permits a free drainage of liquid refrigerant into said outlet header from the 25 pipe as condensed therein, and also so arranged that a pipe of high condensing capacity opens into said outlet header at a point nearer the cooling fluid admission than 30 a pipe of lower condensing capacity, and means located adjacent the inlet header to limit the flow of refrigerant gas into the respective pipes to a quantity substantially equivalent to the condensing capacity of the 35 respective pipe.

4. In a condenser for a refrigerating plant, an inlet and an outlet header, a plurality of condensing pipes in multiple connecting said 40 headers, said pipes being of substantially uniform and the same diameter and arranged substantially in a vertical column, devices to cause water to trickle successively downward from pipe to pipe to chill the same, and an apertured regulating plug located adjacent the inlet header in each pipe, the aperture 45 respectively decreasing in size for each pipe with respect to that for the pipe above it.

5. In a condenser for a refrigerating plant, an inlet and an outlet header, a plurality of 50 condensing pipes in multiple connecting said headers, devices whereby to impart different chilling effects to said respective pipes, the chilling effect being substantially uniform throughout the length of a respective pipe, and means to regulate the flow of gas into 55 each pipe so that substantially the same back pressure prevails at the outlet ends of all pipes.

In testimony whereof, I affix my signature.
